DYE INTERMEDIATE

Leslie G. S. Brooker and William Waldo Williams,
Rochester, N. Y., assignors to Eastman Kodak
Company, Rochester, N. Y., a corporation of
New Jersey

No Drawing. Application August 21, 1940,
Serial No. 353,501

14 Claims. (CL. 260—306)

This invention relates to dye intermediates and to a process for the preparation thereof.

A class of intermediates of value for the preparation of simple cyanine dyes consists of the cyclammonium alkyl quaternary salts containing an alkylmercapto group in the alpha or gamma position, i. e. in one of the so-called reactive positions. Some of these alkyl quaternary salts are, of course, more readily available than others, while the corresponding aryl quaternary salts are wholly unavailable.

The cyclammonium alkyl quaternary salts containing an alkylmercapto group in a reactive position can be prepared by treating a heterocyclic nitrogen base containing an alkylmercapto group with an alkyl salt. However, aryl quaternary salts cannot be prepared by treating a heterocyclic nitrogen base containing an alkylmercapto group, with an aryl salt. Certain cyclammonium alkyl quaternary salts containing an alkylmercapto group can be prepared by treating a cyclammonium alkyl quaternary salt containing a halogen atom, with a mercaptan. However, cyclammonium aryl quaternary salts containing a halogen atom in a reactive position are unknown, so that it has not been possible to attempt to react the aryl quaternary salts with mercaptans. It is known that N-alkylthioquinolones and N-alkylthiobenzothiazolones can be treated with alkyl salts to give substances which have been portrayed as sulfonium compounds (see British Patent 423,792, accepted February 7, 1935), but which may actually be cyclammonium alkyl quaternary salts containing an alkylmercapto group.

We have now found that cyclammonium aryl quaternary salts containing an alkylmercapto group in a reactive position can be prepared by treating a compound such as a N-arylthiobenzothiazolone, i. e. a N-aryl heterocyclic nitrogen base containing, in a reactive position, a doubly bound sulfur atom, with an alkyl salt. Moreover, we have found that new cyanine and new merocyanine dyes can be prepared from such substances.

It is, accordingly, an object of our invention to provide cyclammonium aryl quaternary salts containing an alkylmercapto group in a reactive position. A further object is to provide a process for preparing such aryl quaternary salts. A still further object is to provide new dyes prepared from such aryl quaternary salts and a process for preparing such dyes. Other objects will become apparent hereinafter.

In accordance with our invention, we treat a compound such as a N-arylthiobenzothiazolone with an alkyl salt. As alkyl salts, alkyltoluenesulfonates are advantageously employed. Alkyl iodides and dialkyl sulfates can also be employed. The alkyl salt is advantageously em-

ployed in excess; from one and one-half to two and one-half molecular proportions for each molecular proportion of N-arylthiobenzothiazolone being preferable. Heat accelerates the formation of the benzothiazolium salts. The following example will serve to illustrate the formation of our new benzothiazolium salts.

EXAMPLE 1.—2-methylmercapto-3-phenylbenzothiazolium p-toluenesulfonate

15

12.2 g. (1 mol) of 3-phenyl-2-thiobenzothiazolone and 14.0 g. (1 mol + 50% excess) of methyl-p-toluenesulfonate were heated together upon a steam bath for about 4 hours. The reaction mixture was cooled, washed with two 100 cc. portions of diethyl ether, triturated with 50 cc. of acetone, the acetone mixture chilled and the quaternary salt filtered off and dried in the air. In this manner the quaternary salt was obtained, in 85% yield, as colorless crystals, melting at 176° to 177° C. The p-toluenesulfonate can be converted to the iodide or the perchlorate by treating an aqueous solution thereof with an aqueous solution of a water-soluble metal iodide or perchlorate.

In a similar manner, 2-ethylmercapto-3-phenylbenzothiazolium-p-toluenesulfonate, as well as 2-methylmercapto-3-naphthylbenzothiazolium-p-toluenesulfonate can be prepared.

The 3-phenyl-2-thiobenzothiazolone employed in the above example as well as similar N-aryl compounds can be prepared by treating the corresponding oxo compound (in this specific case 3-phenyl-2-benzothiazolone) with phosphorous pentasulfide in xylene as described in our co-pending application Serial No. 353,500, filed of even date herewith (now U. S. Patent 2,330,203, dated September 28, 1943).

45 Our new benzothiazolium aryl quaternary salts can be condensed with malonic acid in the presence of pyridine to give N-aryl thiacyanines, as illustrated in the following example.

EXAMPLE 2.—3,3'-diphenylthiacyanine iodide

50

2.0 g. (2 mol.) of 2-methylmercapto-3-phenylbenzothiazolium p-toluenesulfonate and 1.0 g. (1 mol. + 100% excess) of malonic acid were placed in 10 cc. of dry pyridine. The mixture

was heated on a steam bath for 45 minutes. The hot reaction mixture was poured into 20 cc. of aqueous sodium iodide solution containing 1.5 g. (1 mol. + 100% excess) of sodium iodide. The resulting mixture was cooled and diluted with 25 cc. of diethyl ether, whereupon the thiacyanine iodide precipitated. It was filtered off, dried in the air. 0.9 g. (64% yield) of crude dye was thus obtained. The dye was twice recrystallized from absolute ethyl alcohol (40 cc. per gram) and obtained, in 36% yield, as glistening yellow crystals which melted above 315° C. The dye sensitized a photographic gelatino-silver-chloride emulsion out to 495 mu with a maximum at about 460 mu.

Our new benzothiazolium aryl quaternary salts can also be condensed, in the presence of an acid-binding agent, with cyclammonium quaternary salts containing a reactive methyl group to give 2'-cyanine dyes, as illustrated in the following examples.

EXAMPLE 3.—1'-ethyl-3-phenylthia-2'-cyanine iodide

1.2 g. (1 mol.) of 3-phenyl-2-thiobenzothiazolone and 0.95 g. (1 mol.) of methyl-p-toluenesulfonate were heated together upon a steam bath for two hours. To the resulting mass were added 1.5 g. (1 mol.) of quinaldine ethiodide, 10 cc. of absolute ethyl alcohol and 0.5 g. (1 mol.) of triethylamine. The resulting mixture was refluxed gently for 3 minutes, cooled and the dye filtered off. 1.4 g. (56% yield) of crude dye was thus obtained. The dye was dissolved in absolute ethyl alcohol and the solution decolorized with "Norite." After a further recrystallization from absolute ethyl alcohol (50 cc. per gram of dye), the dye was obtained, in 14% yield, as orange colored needles, melting at 241° to 242° C. with decomposition. The dye sensitized a photographic gelatino-silver-bromide emulsion to 560 mu with a maximum at 520 mu.

EXAMPLE 4.—1'-ethyl-3-phenylthia-4'-cyanine iodide

1.2 g. (1 mol.) of 3-phenyl-2-thiobenzothiazolone and 0.95 g. (1 mol.) of methyl-p-toluenesulfonate were heated together on a steam bath for four hours. To the resulting mass were added 1.5 g. (1 mol.) of lepidine ethiodide, 10 cc. of absolute ethyl alcohol and 0.5 g. (1 mol.) of triethylamine. The resulting mixture was refluxed for 10 minutes, cooled, diluted with an equal volume of diethyl ether and allowed to stand overnight. The ether layer was decanted and the oily residue was dissolved in 15 cc. of absolute ethyl alcohol, the alcoholic solution chilled and the crude dye filtered off and dried in the air. In this manner, 1.0 g. (40% yield) of dye was obtained. After three recrystallizations from absolute ethyl alcohol (15 cc. per gram of dye), the dye was obtained, in 18% yield, as glistening red

crystals melting at 277° to 279° C. with decomposition. The dye sensitized a photographic silver bromide emulsion to 570 mu with a maximum at about 530 mu.

EXAMPLE 5.—3-ethyl-3'-phenylthiacyanine iodide

1.2 g. (1 mol.) of 3-phenyl-2-thiobenzothiazolone and 0.95 g. (1 mol.) of methyl-p-toluenesulfonate were heated together on a steam bath for two hours. 1.5 g. (1 mol.) of 2-methylbenzothiazole ethiodide, 10 cc. of absolute ethyl alcohol and 0.5 g. (1 mol.) of triethylamine were added to the reaction mixture, and the resulting mixture was refluxed for five minutes, cooled and the dye filtered off. In this manner, 1.2 g. (48% yield) of crude dye was obtained. After two recrystallizations from absolute ethyl alcohol (50 cc. per gram of dye), the dye was obtained, in 32% yield, as yellow crystals, melting at 265° to 266° C. The dye sensitized a photographic gelatino-silver-chloride emulsion to 485 mu with a maximum at 460 mu.

In Examples 3, 4 and 5, where triethylamine is employed as acid-binding agent, other strong organic bases can be used, especially tertiary strong organic bases, such as N-methyl-piperidine, triethanolamine, etc. Still other acid-binding agents, such as sodium or potassium carbonate are very satisfactory. Heat accelerates the formation of the dyes.

In the preparation of photographic emulsions containing our new dyes, it is only necessary to disperse the dyes in the emulsions. The methods of incorporating dyes in emulsions are simple and well known to those skilled in the art. It is convenient to add the dyes from solutions in appropriate solvents. Methanol has proven satisfactory as a solvent for our new dyes. Ethyl alcohol or acetone may also be employed where the solubility of the dyes in methanol is lower than desired.

Sensitization by means of our new dyes is, of course, directed primarily to the ordinarily employed gelatino-silver-halide developing-out emulsions. The dyes are advantageously incorporated in the washed, finished emulsions and should, of course, be uniformly distributed throughout the emulsions.

The concentration of our new dyes in the emulsion can vary widely, i. e. from about 5 to about 100 mgs. per liter of flowable emulsion. The concentration of the dye will vary according to the type of light-sensitive material in the emulsion and according to the effects desired. The suitable and most economical concentration for any given emulsion will be apparent to those skilled in the art upon making the ordinary tests and observations customarily used in the art of emulsion making.

To prepare a gelatino-silver-halide emulsion sensitized with one of our new dyes, the following procedure is satisfactory: A quantity of the dye is dissolved in methyl alcohol or other suitable solvent and a volume of this solution (which may be diluted with water) containing from 5 to 100 mgs. of dye is slowly added to about 1000 cc. of a gelatino-silver-halide emulsion, with stirring. Stirring is continued until the dye is

uniformly distributed throughout the emulsion. With most of our new dyes, 10 to 20 mgs. of dye per liter of emulsion suffices to produce the maximum sensitizing effect with the ordinary gelatino-silver-bromide (including bromide) emulsions. With fine-grain emulsions, which includes most of the ordinarily employed gelatino-silver chloride emulsions, somewhat larger concentrations of dye may be necessary to secure the optimum sensitizing effect.

The above statements are only illustrative and are not to be understood as limiting our invention in any sense, as it will be apparent that our new dyes can be incorporated by other methods in many of the photographic silver halide emulsions customarily employed in the art. For instance, the dyes may be incorporated by bathing a plate or film upon which an emulsion has been coated, in the solution of the dye, in an appropriate solvent. Bathing methods, however, are not to be preferred ordinarily.

What we claim as our invention and desire to be secured by Letters Patent of the United States is:

1. A process for preparing a benzothiazolium aryl quaternary salt comprising treating a N-aryl-2-thiobenzothiazolone with an alkyl-p-toluenesulfonate.

2. A process for preparing a benzothiazolium aryl quaternary salt comprising treating one molecular proportion of N-aryl-2-thiobenzothiazolone with from one and one-half to two and one-half molecular proportions of an alkyl salt.

3. A process for preparing a benzothiazolium aryl quaternary salt comprising treating one molecular proportion of N-aryl-2-thiobenzothiazolone with from one and one-half to two and one-half molecular proportions of an alkyl-p-toluenesulfonate.

4. A process for preparing a benzothiazolium phenyl quaternary salt comprising treating a N-phenyl-2-thiobenzothiazolone with an alkyl salt.

5. A process for preparing a benzothiazolium phenyl quaternary salt comprising treating a

N-phenyl-2-thiobenzothiazolone with an alkyl-p-toluenesulfonate.

6. A process for preparing a benzothiazolium phenyl quaternary salt comprising treating one 5 molecular proportion of a N-phenyl-2-thiobenzothiazolone with from about one and one-half to about two and one-half molecular proportions of an alkyl salt.

7. A process for preparing a benzothiazolium 10 phenyl quaternary salt comprising treating one molecular proportion of a N-phenyl-2-thiobenzothiazolone with from about one and one-half to about two and one-half molecular proportions of an alkyl-p-toluenesulfonate.

15 8. A process for preparing a benzothiazolium phenyl quaternary salt comprising treating a N-phenyl-2-thiobenzothiazolone with methyl-p-tolene-sulfonate.

9. A process for preparing a benzothiazolium 20 phenyl quaternary salt comprising treating one molecular proportion of a N-phenyl-2-thiobenzothiazolone with from one and one-half to two and one-half molecular proportions of methyl-p-toluenesulfonate.

25 10. A benzothiazolium aryl quaternary salt containing an alkylmercapto group in the 2-position.

11. A benzothiazolium aryl quaternary salt containing a methylmercapto group in the 2-position.

30 12. A benzothiazolium phenyl quaternary salt containing an alkylmercapto group in the 2-position.

13. A benzothiazolium phenyl quaternary salt 35 containing a methylmercapto group in the 2-position.

14. A benzothiazolium quaternary salt having the following formula:

40
